SPRAYING DEVICE

Carl S. Meyerhoefer, Brooklyn, N. Y., assignor to
 Lewyt Corporation, Brooklyn, N. Y., a corpora-
 tion of New York

Application June 26, 1947, Serial No. 757,245

5 Claims. (Cl. 299—89)

1

This invention relates to a functionally and structurally improved liquid-spraying device and aims more particularly, to provide a unit for use in connection with vacuum cleaners or similar apparatus.

As is well appreciated, numerous spraying devices have been developed for connection to the outlet end of, for example, a vacuum cleaner. These devices have in many instances been unsatisfactory in that they were frequently expensive and/or offered objections in their functioning.

It is an object of this invention to provide an improved unit which will be primarily designed for use by attachment to the outlet end of a vacuum cleaner or similar apparatus developing relatively low pressures. This unit will embody structures such that it will be positive in operation. Accordingly, satisfactory results may be obtained without the operator possessing any special skill or training in the use of this device.

A further object is that of providing a device in which the flow of air and accordingly the body of the spray may be regulated with nicety, whether relatively viscous or light liquids are being used in the device.

A still further object is that of designing a spraying device in which—even if the parts should have sufficient tolerances to cause small air leakages—such leakages will not result in the apparatus continuing to function after the operator desires that it cease to eject a spray.

An additional object is that of furnishing a unit of this type which will embody relatively few parts, each individually simple and rugged in construction, such parts being capable of manufacture largely by quantity production methods and being susceptible to assembly by unskilled labor to furnish an apparatus functioning over long periods of time with freedom from all difficulties.

With these and other objects in mind, reference is had to the attached sheet of drawings illustrating one practical embodiment of the invention and in which:

Fig. 1 is a top plan view of the device;

Fig. 2 is a sectional side view taken along the lines 2—2 and in the direction of the arrows as indicated in Fig. 1;

Fig. 3 is a front view of the attachment; and

Fig. 4 is a transverse sectional view taken along the lines 4—4 and in the direction of the arrows as indicated in Fig. 1.

In these views the numeral 5 indicates a jar

2

or container which may be formed of glass or any other suitable material. Disposed upon this container is a cap or operating head. To connect the two units to each other, the cap may be formed with a downwardly extending threaded flange 6; a gasket 7 being provided to assure of a substantially air-tight seal between the parts. Obviously, any other form of coupling might be employed to assure this connection and 10 the body of the container 5 could embrace any desired configuration suitable to receive varnishes, lacquers, paints, germicides, insecticides or other liquids.

The cap or head structure conveniently includes an upper portion 8 which may be integral with the flange 6 and which is conveniently domed. Centrally of this portion a tube 9 may extend transversely across the assembly. The inner end of this tube may be tapered as at 10 or 15 otherwise suitably formed, to be coupled to an outlet or hose (not shown) by means of which it can be connected to a source of pressure such as the outlet end of a more or less conventional vacuum cleaning apparatus. The tube 9 adjacent its outer end conveniently terminates in an inwardly extending lip portion 11 defining an opening 12.

Extending across the opening may be supporting arms 13 which mount a hub 14. The latter has a central opening which may be counterbored in its outer end. A flanged nozzle element 15 may have its flange resting against the outer face of the hub 14 and mount at its inner end, the end of a tube 16. It is obvious that incident to the counterboring of the hub 14, the nozzle 15 carrying the end of the tube 16 may have a force-fit with the hub. Therefore, an accidental separation of these parts will not occur. However, it is obvious that other forms of connection might be employed.

The lower surface of the tube 9 is formed with an opening of an area such that the tube 16 may pass through the same. Adjacent such opening, a circular flange 17 may be provided. 35 A packing plug 18 may be interposed between the flange and tube so as to prevent the passage of air between the tube 9 and the interior of the container 5. The length of the tube 16 should be such that—as illustrated—it may normally 40 rest adjacent the base of container 5. Also, it may be curved forwardly within that container.

A control valve is provided by utilizing, for example, a tapered body 19 which seats within a corresponding contoured opening in the lower surface of the tube 9. Such seating is assured

55

by employing a spring 20 which bears against the lower surface of the tube 9 and has its opposite end bearing, for example, in a groove 21 formed in a knurled knob 22. The head of the latter projects through an opening formed in the upper surface of tube 9. The knob 22 is bored and formed with internal threads as at 23. The valve body 19 is continued in the form of a stem which is correspondingly threaded as at 24. Therefore, it is apparent that these parts may be coupled and a depression of knob 22 will result in a projection of the stem 24 and body 19. This will have the effect of unseating that valve body and allowing a flow of air from the tube 9 into the interior of the receptacle 5.

It will also be apparent that if a greater or lesser amount of air pressure is desired, the operator may achieve this without sacrificing the ease of operation permissible by fully projecting the knob 22. This result is obtained incident to the adjustment provided by rotating the knob 22 with respect to the threads of the stem 24. By such rotation, the overall distance between the valve body 19 and knob 22 will be increased or decreased. To prevent a turning of the valve 19 and stem 24, the lower end of the former may terminate in a non-circular head portion 25. Extending from the underface of tube 9 are any suitable number of lips or fins 26 which cooperate with the head 25 to guide the same. In other words, they will permit an axial movement of the head but not a rotation thereof. The inner ends of these fins may be turned inwardly as at 27. This will have the effect that a stop is provided limiting the axial movement of valve 19. Accordingly, there will be no danger of an operator turning the knob 22 to a point at which it disengages from the stem 24 with the result that the valve assembly falls into the container 5 and becomes immersed in the liquid therein. At the same time it will be apparent, incident to the fact that the spring 20 rides within the groove 21, an accidental turning of the knob 22 will not occur with respect to the valve and its stem.

In using an apparatus of this type, it will be understood that the container 5 is filled to a suitable depth with the liquid to be sprayed. Thereafter, the operating head or cap is coupled to the body 5. The inner end of the tube 9 being coupled to a suitable source of air under pressure, it follows that that air will be discharged through the tube 9 and out through the openings 12. Under these circumstances, no spray will be ejected from the nozzle 15. Assuming that the knob 22 has been adjusted so that a projection of the same towards the axis of the tube will cause the valve 19 to be unseated, a limited amount of air will flow past the valve 19 and act on the liquid within the receptacle 5 when pressure is brought to bear on the knob 22. The amount of air so acting on the liquid may be increased or decreased by simply turning the knob 22. In each instance, however, when the device is actuated the operator will be free to project the knob to the limit of its movement. Obviously, the greater amount of air flowing past the valve 19, the greater will be the pressure exerted upon the upper surface of the liquid within receptacle 5. Therefore, the greater will be the discharge of that liquid through the tube 16 and the nozzle 15.

As it is so discharged, the air stream flowing through the openings 12 will be concentric in its flow with respect to the jet of liquid which

is being discharged. Therefore, a proper spray will be projected from the device. The air pressure supply being substantially constant, the volume of air discharged through opening 12 will remain uniform within close limits. Depending upon the adjustment of valve 19, however, a greater or lesser amount of liquid will be ejected from the nozzle 15. Therefore, within the control of the operator, a relatively dense or fine spray may be produced. Under all circumstances it will be understood that with the valve 19 open, the flow of air through the opening 12 will produce a certain amount of suction at the outer end of the nozzle 15, which function will facilitate the discharge of the liquid.

Under normal circumstances, a release of the valve 22 will result in the interruption of air flow through the tube 9 into the receptacle. However, under certain circumstances—either due to particles of foreign material or otherwise—the valve 19 may remain minutely unseated even when pressure on the knob 22 is released. This would normally have the result that a small amount of liquid would be forced from the nozzle 15 incident to the minute flow of air into the receptacle. This, obviously, is undesirable. To prevent such an occurrence, portion 8 may be formed with a vent hole 28. The area of this opening while small, would be adequate to relieve the pressure exerted by a small air flow into the container. Therefore, no dripping or slight discharge of liquid from the nozzle 15 will occur so long as the knob 22 is released.

Thus, among others, the several objects of the invention as aforesaid are achieved. Obviously numerous changes in construction and rearrangement of the parts might be resorted to without departing from the spirit of the invention as defined by the claims.

40 What I claim is:

1. A spraying device including in combination a cap for application to the upper end of a receptacle, an air-conducting tube extending across said cap and having a discharge end, an unobstructed liquid-conducting tube extending within and to a point adjacent the discharge end of said air-conducting tube, means for securing said liquid-conducting tube against relative movement within and with respect to said air-conducting tube, said latter tube being formed with aligned openings in its diametrically opposed upper and lower surfaces and at points intermediate its ends, a valve to seat against the surfaces of such tube adjacent the opening in its lower face, an actuator connected to said valve and slidably mounted within the opening in the upper surface of such tube to extend above the same, said actuator constantly obstructing a flow of air through said latter opening, means for normally maintaining said valve in closed position and said actuator upon being depressed shifting the valve to a position where it does not obstruct a flow of air through the opening in the lower surface of the air-conducting tube.

2. A spraying device including in combination a cap for application to the upper end of a receptacle, an air-conducting tube extending across said cap and having a discharge end, an unobstructed liquid-conducting tube extending within and to a point adjacent the discharge end of said air-conducting tube, means for securing said liquid-conducting tube against relative movement within and with respect to said air-conducting tube, said latter tube being formed

with aligned openings in its diametrically opposed upper and lower surfaces and at points intermediate its ends, a valve to seat against the surfaces of such tube adjacent the opening in its lower face, an actuator connected to said valve and slidably mounted within the opening in the upper surface of such tube to extend above the same, said actuator constantly obstructing a flow of air through said latter opening, a spring having one end bearing against the inner face of said air-conducting tube adjacent the opening in its lower surface, said spring extending transversely across the bore of said air-conducting tube, the opposite spring end bearing against said actuator to normally maintain the valve in closed position and said actuator, upon being shifted inwardly of said air-conducting tube, causing said valve to move to a position at which it does not obstruct a flow of air through the opening formed in the lower surface of said air-conducting tube.

3. A spraying device including in combination a cap for application to the upper end of a receptacle, an air-conducting tube extending across said cap and having a discharge end, an unobstructed liquid-conducting tube extending within and to a point adjacent the discharge end of said air-conducting tube, means for securing said liquid-conducting tube against relative movement within and with respect to said air-conducting tube, said latter tube being formed with aligned openings in its diametrically opposed upper and lower surfaces and at points intermediate its ends, a conical valve having its reduced end extending through the opening in the lower surface of said air-conducting tube and into the space defined by said cap, an actuator connected to said valve and slidably mounted within the opening in the upper surface of such tube to extend above the same, said actuator constantly obstructing said latter opening to prevent substantial flow of air therethrough, means for normally maintaining said valve in closed position and said actuator being shiftable in a downward direction to cause said valve to move to a position at which it does not obstruct the opening in the lower surface of said air-conducting tube.

4. A spraying device including in combination a cap for application to the upper end of a receptacle, an air-conducting tube extending across said cap and having a discharge end, an unobstructed liquid-conducting tube extending within and to a point adjacent the discharge end of said air-conducting tube, means for securing said liquid-conducting tube against relative movement within and with respect to said air-conducting tube, said latter tube being formed with aligned openings in its diametrically opposed upper and lower surfaces and at points intermediate its ends, a valve to seat against the surfaces of such tube adjacent the opening in its lower face, an actuator connected to said valve and slidably mounted within the opening in the upper surface of such tube to extend above the same, said

actuator constantly obstructing a flow of air through said latter opening, means for normally maintaining said valve in closed position, said actuator upon being depressed shifting the valve to a position where it does not obstruct a flow of air through the opening in the lower surface of the air-conducting tube, said valve extending below the lower surface of said air-conducting tube into the space defined by said cap and confining means secured to said air-conducting tube and extending below the lower surface of the same to restrain said valve against rotation and guide the latter in its movements.

5. A spraying device including in combination a cap for application to the upper end of a receptacle, an air-conducting tube extending across said cap and having a discharge end, an unobstructed liquid-conducting tube extending within and to a point adjacent the discharge end of said air-conducting tube, means for securing said liquid-conducting tube against relative movement within and with respect to said air-conducting tube, said latter tube being formed with aligned openings in its diametrically opposed upper and lower surfaces and at points intermediate its ends, a valve to seat against the surfaces of such tube adjacent the opening in its lower face, an actuator connected to said valve and slidably mounted within the opening in the upper surface of such tube to extend above the same, said actuator constantly obstructing a flow of air through said latter opening, means for normally maintaining said valve in closed position, said actuator upon being depressed shifting the valve to a position where it does not obstruct a flow of air through the opening in the lower surface of the air-conducting tube and means forming a part of the connection between said valve and actuator whereby the distance between the upper surface of the latter and said valve may be varied to adjust the parts.
